UNITED STATES PATENT OFFICE.

HARRY BRIDGMAN, OF NEW YORK, N. Y., ASSIGNOR TO BRIDGMAN & RUBIN, INC., OF NEW YORK, N. Y., A CORPORATION OF NEW YORK.

MACHINE FOR FOLDING AND SECURING BOX-COVER MARGINS.

Application filed May 13, 1926. Serial No. 108,851.

My invention relates to a machine designed for turning and folding inward, and securing, projecting margins of cover paper of a strip-covered box shell, or for analogous purposes.

Among the principal objects of the invention are: to provide a machine which, preferably, is entirely automatic; which is designed to include an automatic feed of the covered box shells, or to co-operate with automatic feeding mechanism; which then manipulates the shells and their projecting cover margins, without the use of any "plunger" or internal form, to turn the open-edge margins horizontally inward and then down against inner faces of the box walls, and press the margins into adhesive connection with the shell walls by a clinching or pinching operation in which the stresses in the pressing mechanisms are practically equalized or self-contained; to also, when desired, fold and secure projecting bottom cover margins upon the box bottom; and to so construct and arrange the parts that they are easily adjustable for different box sizes.

Another object which is in one aspect subordinate to other objects, but in a preferred embodiment of the invention is of great importance in connection with other features, is to provide hydraulic means for operating certain parts of the mechanism, and especially the pressing devices.

The invention mechanism is especially useful for handling box shells, the walls of which have been covered by a stripping operation in which a strip of glued paper is wound about the walls, severed and overlapped to complete the covering of outer wall surfaces. This operation leaves margins of the cover projecting above and below the walls at the top and bottom of the box respectively. It has been customary in the art to turn and secure these margins by hand, the upper margins being turned in and down against inner marginal faces of the walls, and the bottom margins being turned and pressed horizontally against the box bottom. The present machine provides means for rapidly and automatically effecting certain of these turning operations, and especially the inturning and pressing of the top margins and also, when desired, certain of the bottom margins, usually those projecting below the side walls of the box. The

only hand margin turning operation then necessary is that of turning the end bottom margins and securing them to the box bottom, and this may be done by the operative who performs the stripping operation when that is done by hand.

The characteristics and advantages of the invention are further sufficiently explained in connection with the following detail description of the accompanying drawings, which show a representative embodiment of the invention. After considering this example, skilled persons will understand that many variations may be made, and I contemplate the employment of any structures that are within the scope of the appended claims.

In the drawings:

Fig. 1 is a view in vertical, longitudinal, section in the plane 1—1, Fig. 2.

Fig. 2 is a vertical, transverse section in the plane 2—2, Fig. 1.

Fig. 3 is a section, similar to Fig. 2, with some parts omitted, showing a different operative position.

Fig. 4 is a top plan, with some parts sectioned.

Fig. 5 is a fragmentary, top-plan detail of the turning and pressing bars and one of the hydraulic operating devices.

Fig. 6 is a bottom plan of the same.

Fig. 7 is a sectional detail of the turning and pressing bars and bottom-margin turner.

Fig. 8 is a detail of operating means for the hydraulic actuator or driver.

Fig. 9 is perspective view of a strip-covered box, in condition for supply to the present machine.

The general plan of operations is briefly described as follows:—The box shell B, to the side and end walls of which the cover paper C has been applied, usually by a stripping operation, has the top cover margins M projecting above the upper wall edges all around the box, and may also have bottom side wall margins M¹ projecting below the box bottom at the side thereof. The end bottom margins have been turned in and affixed to the box bottom by hand operations or otherwise. These covered boxes are advanced in a series, end first, to a position below margin turning and pressing mechanism. The box is then elevated to bring the upper shell edges substantially in horizontal align-

ment with turning and pressing devices, which are at this time horizontally retracted. There are four of these devices corresponding to the four sides of the box. The devices are bodily movable convergently and divergently and each includes an inner and an outer bar with means for moving these bars relatively, to provide a box-wall-receiving space and to press the wall between the bars. The outer bars have their inner faces depending below the lower edges of the inner bars, which are rounded or cam-shaped in cross section. The turning and pressing devices are moved bodily convergently, while the two bars of each device are separated, and in this movement the rounded or cam-like faces of the inner bars turn the upper cover margins horizontally inward and at the same time act upon the upper edges of the box walls to level the box. In this convergent movement of the turning devices bottom margin turning devices may also act to turn and preliminarily press the bottom side cover margins against the box bottom. At the end of the stated convergent movement the inner bars of all the pressing devices, which have beveled ends, are brought together so that these bars provide an inner, rectangular box form or guide. The outer bars which also have beveled ends are brought nearly to end-contact, providing an accurate outer form or guide. Lower faces of the outer bars also engage upper portions of the box walls and positively position or center the box and correct any box irregularities, so that the walls are accurately positioned for movement into the space between the inner and outer bars.

The box is now again raised to bring its upper wall margins between the spaced inner and outer bars, and in this movement the rounded or cam-like bottom faces of the inner bars turn the cover margins down parallel to inner wall faces. The outer bars are now moved convergently or toward the corresponding inner bars to press the cover margins firmly in position on the box walls, to which they adhere by virtue of adhesive which was applied in the stripping operation. The outer bars are refracted or withdrawn divergently to free the box walls from pressure; the box is lowered clear from the turning and pressing devices while the latter are moved bodily divergently ready for another action; the box is then moved onward for discharge, and in this motion the bottom margins may be additionally pressed and secured in position. A positive ejector is provided to definitely move the box down clear from the turning and pressing devices, after the margin pressing operation. Another box is then positioned below the turning and pressing devices and elevated, and the stated cycle continues indefinitely.

Mechanism for performing the stated

process or series of operations, is provided in the present specific example, as follows:—

The machine is built upon or about a frame which includes side standards 1, having flared bases 2 and connected by various cross bars or members such as 3, 4, etc. Desirably, the entire machine is supported, for easy movability, upon small wheels 5 mounted on journals on cross bars 4.

The cross bars 3 support a longitudinal bar 7 on which are mounted pulley yokes 8 and 9 which may, if necessary, be adjustable longitudinally of the supporting bar by means of slots therein, and secured by nuts 10.

A shaft 11 in yoke 9 supports three spaced pulleys 12 and 13. A shaft 14 in yoke 8 supports a pulley 15 in line with the center pulley 12 on shaft 11. A main feed belt 16 runs on pulleys 12 and 15 and the upper stretch of the belt and the weight of boxes thereon is borne by a rail 17 supported by the yokes. Carry-off belts 18 run about the outer pulleys 13 on shaft 11 to any convenient point of disposal of the finished boxes. The rearward portions of the belts are of course supported on suitable pulleys (not shown). The upper stretches of belts 18 are also supported by rails 19 for a purpose referred to hereafter. The conveyor belts are driven in any convenient way, specifically, in this example, by a belt 20 passing about a pulley 21 on shaft 11 and also about a pulley 22 on a shaft 23 aligned with the shaft of a motor 24 mounted on longitudinal frame bars 25.

The boxes are guided in their movement to the turning mechanism by side rails 26, and similar side guide rails 27 are provided adjacent belts 18 to guide the finished boxes.

A top frame member 30 is supported for vertical adjustment on side frame uprights 1. This top frame includes transverse arms 31 and longitudinal arms 32. The ends of the transverse arms are connected to vertical rack bars 33 which pass through guides 34 on the side frame members 1. A shaft 35 is mounted in bearings in frame members 1 and has pinions 36 engaging the teeth of the rack bars and also a polygonal formation 37 on one end to receive a wrench or similar tool for rotating the shaft to raise and lower the rack bars, and so to vertically adjust the top frame member. This adjustment is fixed by setting up screws 38 to lock the bars in their guides.

The top frame member carries the turning and pressing mechanism which consists of four units or "turning and pressing heads" each of which includes a frame structure having a base 40 adjustably connected to a slide bar 41, which is mounted for reciprocation in guides 42 in one of the top frame arms. The turning head base is provided with a bolt 43 passing through a slot 44 in

corresponding slide 41 and the head of the bolt acts on a spacing sleeve 46 to lock the turning mechanism in adjusted position on this slide. Each slide has a cam roller 47, 5 engaging one of the spirally directed cam channels 48 in a cam wheel 49 mounted for oscillation on a hollow spindle 50 secured at the center of the top frame member. The cam wheel is oscillated by a pitman 51 connected to an arm 52 having a hub 53 mounted in a bearing sleeve 54 connected to the top frame member by a bracket 55. The hub 53 is splined on a vertical shaft 56 mounted in a lower bearing 57 so that arm 52 is connected to oscillate with the shaft and is free 10 to slide thereon in the adjustment of the top frame member. At its lower end shaft 56 has an arm 58 provided with a cam roller 59 running in a cam track in a cam body 61 fixed on a transverse countershaft 62. This countershaft is driven from the motor driven shaft 23 by a worm 64 thereon, engaging a worm gear 65 on shaft 62.

The base 40 of each turning and pressing head is provided with an inwardly directed strut 70 supporting an inner turning and pressing bar 71. While other materials may be used, this, and the other co-operating bar referred to hereafter are desirably made of wood so that they may be cheaply and conveniently shaped and dimensioned for different box sizes, sets of these bars being provided for boxes of different sizes, or the bars may be easily cut off at the ends to fit any box dimensions. The ends 73 of these bars are beveled at an angle of 45° so that the meeting ends of the four inner bars 71, as shown in top plan, Fig. 5, fit closely together when the heads are in inward position. The lower portions of the bar ends are slightly cut away, as shown in bottom plan, Fig. 6, to provide a clearance at 74, the width of this clearance being somewhat exaggerated in the drawing. This clearance prevents 40 pinching the upstanding cover margin corners between the bar ends, as the bars converge in turning the margins horizontally.

It is desirable to mount the bars for free endwise movement so that they will automatically adjust themselves in the lengthwise direction as their ends contact in the convergent movement of the heads, and this manner of mounting also permits easy and quick removal and replacement of the bars, 50 for instance, when the box size is changed. For this purpose the bars are provided with top and side channels 76 engaging ribs 77 formed on strut 70 and on the lower edge of a holding plate 78 respectively. The bars may be slid endwise into position and will then automatically adjust themselves in the manner above mentioned in the operation of the machine, and there is no tendency to excessive longitudinal displacement of the bars when the heads are retracted, because

the bars are brought definitely to approximately centered position in their supports at each convergent movement of the head. The bottom faces of the inner bars 71 are rounded or beveled toward each side from 55 the bottom 79 so that the opposite beveled or rounded bar faces have a cam-like margin turning or box edge directing effect, as further referred to below.

Co-operating with each inner bar 71 is an outer pressing bar 80, the inner vertical face dimension of which is such that it extends substantially below the lower edge of the inner bar. Each of the outer bars is slidably arranged in a manner similar to the support of the inner bar, in a bracket 81 the center of which is connected to a plunger 82 and end portions of which are connected to other plungers 83. The ends of the outer bars are beveled at an angle of 45° so that they will fit together and adjust themselves lengthwise in the convergent movement of the heads, in a manner sufficiently understood from the explanation of the inner bars. The center supporting plunger of each 60 bracket 81 passes through a guide hole 84 in an inner diaphragm support 85 formed as a part of the pressing head frame, and the outer plungers 83 pass through guide holes in ears 86 formed in the diaphragm support. A hydraulic diaphragm 87 is clamped to an outer annular face of the support by hydraulic casing 88 secured to the support 85 by screws 89. The central plunger 82 has a plate 90 resting against the diaphragm and is urged outwardly by a spring 91 compressed between the plate and the diaphragm support. The hydraulic chamber formed in each diaphragm casing 88 is filled with a suitable power conveying liquid and is connected by means of a nipple 92 and flexible pipe 93 to a hydraulic driver of generally similar construction to the pressing diaphragm and sufficiently referred to hereafter.

When it is desired to turn in projecting lower side cover margins, the brackets 81 of each turning and pressing mechanism is provided with depending guide members 100 on which brackets 101 are slidably mounted 115 and secured in adjusted position by screws 102 passing through slots 103 in the guides. Brackets 101 provide end bearings for the shaft 104 of a roll 105 which may be long enough to turn the bottom side cover margins of the longest box that the machine is designed to handle. The supporting brackets are adjusted vertically with regard to the depth of the box so that when the heads move inward to effect the horizontal in-turning of the top cover margins, the rolls 105 at the same time run under the longitudinal bottom corners of the box with slight pressure thereon, and turn the bottom cover margins M' inward and press them against 125 130

the box bottom to which they adhere by reason of the adhesive applied in the striping operation. These bottom turning devices may be omitted if the bottom margin turning operation is unnecessary.

An ejector is provided, consisting of a plate 110, the plan dimensions of which are small enough to fit within the smallest boxes to be handled or plates of different dimensions may be provided if necessary or desirable, for different box plan dimensions. The ejector plate is carried on the lower end of a plunger 111 which passes through the hollow spindle 50 above mentioned, and is connected at its upper end by links 112 to a lever arm 113 fulcrumed at 114 in a bracket 115 extending upward from one of the side frame pedestals 1. A link 116 is pivotally connected to the lever arm and also to a cam yoke and follower 117, co-operating with cam 118 on transverse cam shaft 62. The lever is urged downward or to box ejecting position by a spring 120 tensioned between link 116 at a fixed point on the frame.

Means are provided for approximately positioning the successive boxes below the turning and pressing mechanism and for elevating them for the initial turning operation, as follows:—Longitudinal lifter bars 125 are located at opposite sides of feed belt 16, below the turning mechanism. Normally, the upper edges of these bars are slightly below the level of the upper belt stretches. At their rearward end the bars have upstanding stop fingers 126 to engage the forward end of the box as the feed belt moves it over the lifting bars and check the box in the proper longitudinal position, the lateral position of the box being regulated by the side guide rails 26. The lifting rails 125 are mounted on plungers 130 which are arranged for vertical reciprocation in guides 131 carried by brackets 132 adjustably secured on a cross bar 133. The lower ends of the vertical bars 130 are slotted to engage a horizontal lifting bar 134 connected to a slide mounted for vertical reciprocation in guide 135 on transverse frame member 136. The slide is reciprocated by link 137 connected to a lever arm 138 fulcrumed in bracket 139 and provided with a cam roll 140 running in a cam channel 141 in cam body 140 fixed on the transverse cam shaft 62. The brackets 132 and lifting rails 125 are adjusted laterally toward and from the center line of the machine, in accordance with box width by a screw 150 mounted in bearings in frame uprights 1 and secured against end motion. The screw passes through nuts 151 secured to the brackets and has at one end a polygonal formation 152 for engagement by a wrench or other suitable tool to rotate the screw and thus adjust the lifting rails, this adjustment being permitted without disturbance of the

operative connection of the vertical bars 130 by the lateral sliding of the bar slots 130^a on the horizontal operating bar 134.

For energizing the hydraulic pressing devices above mentioned, a hydraulic actuator 70 is provided, comprising a diaphragm frame 160 secured to frame bar 136 and having a piston guide 162. A diaphragm 163 and diaphragm casing 164 are secured to the diaphragm frame, substantially as described in 75 regard to the hydraulic driven devices. A filling hole and screw plug 165 are provided for recharging the hydraulic casing 164 with a suitable liquid if the supply is depleted by leakage or otherwise. The diaphragm acts on a plate 166 secured to a piston 167 reciprocably located in the guide 162. This piston is acted on by a plunger 168 reciprocably located in a guide in transverse frame member 136. The plunger is connected to a yoke 85 169 fitting about the cam shaft 62 and having a cam roller 170 engaging in a channel in a cam body 171 fixed on the shaft.

At the center of the diaphragm casing is a threaded bore 180 to receive a branched fitting 181, from which the flexible pipes 93, above mentioned, lead to the nipples 92 of the various driven hydraulic devices.

Any suitable means may be provided for regulating the movement of boxes to initial 95 position. One known mechanism is illustrated for this purpose and no claim is made to it except generally as suitable feed-regulating means, in connection with other features of the invention. This mechanism includes a stop finger 190 carried by an arm 191 on a rock shaft 192, which is mounted in a bearing at the end of a bracket 193 extending from the forward longitudinal arm 32 of top plate 30. The rock shaft also has another arm 194 adjustably secured to a link 195 which is actuated by a bellerank 196 fulcrumed at 197 and provided with a cam roller 198 engaging an actuating cam on cam body 61, previously mentioned.

A gauging device is desirably provided to facilitate the adjustment of the top frame member 30 in accordance with box height. This comprises a lower gauge member 210 projecting from the fixed frame bracket 115 and an upper gauge member or finger 211 projecting from one of the top plate cross arms 31. The gauge members are so located that the distance between their confronting faces is equal to the distance between the upper faces of the box lifting bars 125 and the lower edges of the inner turning bars 71. Therefore, in adjusting the top plate for a given box height, it is only necessary to place the box bottom on the lower gauge 210 and rotate the adjusting shaft 35 until the upper gauge member is close to or touches the upper edge of the box wall and thereupon the turning and pressing mechanism are properly located with respect to their verti- 120 125 130

cal position for operating upon the particular box or others of the same height.

Means are also provided to hold the boxes as they pass onward from the turning and pressing mechanism firmly upon the carry-off conveyor belts 18 to further press and secure the bottom side cover margins in position. For this purpose one or more rollers 220 are provided, supported by brackets 221 from longitudinal top frame member 32, the brackets being dimensioned so that when the top frame plate is adjusted for a box of particular height, the horizontal holding or pressing rolls will bear upon the upper edges 16 of the box walls as it moves on the carry-off belt 18 and thus press the bottom cover margins against the box bottom, the belt supporting rails 19 serving to keep the upper belt stretches in horizontal alignment to resist the roller pressure. Only one roll is shown in the drawing, but a series of rolls may evidently be provided if necessary or desirable.

When the boxes placed upon the feed end 25 of conveyor belt 16 have downwardly projecting lower side cover margins, such as M¹, Fig. 9, these margins do not come in contact with any part of the mechanism, since the boxes are supported by the feed belt only along their central zone, and the cover margins project down alongside the brackets which carry the side guide rails 26, as easily understood in Fig. 3. As the rear end wall of each successive box approaches the stop member 190, that member is lowered to active position by its cam mechanism and stops the box in the position shown in Fig. 1. After turning and pressing operations upon the preceding box, and as that box moves onward, the stop finger is withdrawn and the box moves on by the traction of its supporting belt until stopped by its forward end engaging stop fingers 126, which are then projected above the path of box movement. At this time the turning and pressing heads are withdrawn laterally. The cam mechanism above described now raises the elevated rails 125 and the box is moved upward until the upper edges of the shell walls are level with the bottom of the inner turning bars 71. The turning heads are now moved simultaneously inward or convergently and in this movement the round inner faces of the inner bars engage the upper edges of the box shell walls (or actually the cover paper superposed upon the walls). This convergent movement of the inner bar serves to correct any tilting of the box in a horizontal plane. Thus, if one wall edge is slightly higher than the others, the round formation of the bar will press that wall downward into the proper plane. The continuous inward movement of the bar, causes its round or beveled face to turn the projecting cover margins M hori-

zontally inward, and the clearances at 74, Fig. 6, also prevent pinching of the upstanding corner formations as the ends of the bars converge. The outer faces of the inner bars are now in the approximate vertical planes of the inner box shell walls and the inner faces of the outer bars have been brought against the outer faces of the box walls to finally and positively adjust the box or center it in the longitudinal plane. In the convergent movement of the heads, the rolls 105 are moved inward to engage the lower longitudinal box corners and with slight pressure run under the box bottoms and turn and press the projecting lower side cover margins M¹ against the bottom of the box to which they adhere by reason of adhesive applied in connection with the stripping operation.

In the convergent movement of the turning heads, the bars are separated, as shown in Figs. 1 and 3. The box is now moved upward by another small upward movement of the lifting rails 125 to carry the upper shell wall margins up between the inner and outer pressing bars, as shown in Fig. 3. In the upward movement of the box the outer rounded or cam formation of the bottom face of the inner turning bars 71, causes the bars to move within the shell walls and simultaneously turn the upper cover margins down parallel to the shell faces. The hydraulic driving mechanism is now actuated to cause all of the hydraulic diaphragms or motor mechanisms to move the outer pressing bars forcibly inward and press the down turned cover margins firmly against inner surfaces of the shell walls. The outer bars are now retracted to free the box and the ejector is moved downward as the elevating rails move downward to definitely eject the box from the pressing devices. As the box approaches the conveyor level, the pressing heads are withdrawn laterally. When the box bottom again rests on the conveyor belt 16, downward movement of the lifting rails is continued, until the stop fingers 126 are below level of the box bottom, the boxes thereupon move on away from the turning and pressing positions by belt 16 and carry-off belts 18, and as the boxes pass under the top pressing roll or rolls 220, the bottom side cover margins are additionally pressed and secured in position, as sufficiently explained above. The carry-off belts 18 extend to any convenient point for disposition of the finished boxes.

A peculiar and important feature of the mechanism, as above described, is that the same devices, namely, bars 71 serve to level the box to turn the cover margins horizontally, and then to turn them downward by co-operative action of the box-elevating means. In other words, the horizontal turn-

ing is effected by lateral movement of the bars and the vertical turning by movement of the box in relation to the bars. The same bars also co-operate with the other movable 5 presser bars to press the margins firmly in position, and it is to be especially noted that in the pressing action the strains on the pressing mechanism are self-contained, that is to say, the thrusts are balanced and 10 taken up entirely in the mechanism carried by each of the pressing heads. There is thus no strain imposed on the main machine or in the box walls, and no tendency to distort the box; and especially these operations are carried on without the use of any 15 internal plunger or form, such as is ordinarily used in box forming and margin turning operations, and which requires a more complicated structure and also more intricate operations, requiring more time and reducing the output capacity and of course, correspondingly increasing the cost 20 of the boxes. The present machine, by reason of the above described structural features and mode of operation, also dispenses with other intricate or complicated features of previously known machines, such as turn-in blades or fingers, which must be advanced 25 and retracted, subsequently acting plungers or forms to effect the vertical turning, and 30 pressing devices to press the box margins against the form.

While hydraulic operating mechanism is not necessarily employed for the pressing 35 operation, and in the broader aspect of the invention I contemplate the use of any suitable mechanism for this purpose, in a more limited aspect of the invention the use of such hydraulic mechanism, as above explained, or the equivalent, is very important, since 40 it materially simplifies the machine in a structural sense and also permits the positive and forcible actuation of the pressers and especially permits them to be actuated 45 in such a way that the strains set up in them are self-contained in the manner above referred to. To provide this result or function with purely mechanical devices would involve much greater complication and expense.

I claim:—

1. Box margin folding mechanism comprising a plurality of convergently movable margin folding devices, means for approximately positioning with relation to said devices a box having projecting cover margins, means for moving the devices convergently to accurately position the box and turn the cover margins inward, and means for then 55 moving the box relatively to said devices to turn the cover margins down against inner faces of the box walls.

2. Box margin folding mechanism comprising a plurality of convergently movable 60 margin folding devices, means for approx-

imately positioning with relation to said devices a box having projecting cover margins, means for moving the devices convergently to turn the cover margins inward and at the same time by pressure upon the box edges 65 to position it accurately with relation to the plane of movement of said devices, and means for then moving the box relatively to said devices to turn the cover margins down against inner faces of the box walls. 75

3. Box margin folding mechanism comprising a plurality of convergently movable margin manipulating instrumentalities, means for positioning a box with projecting cover margins adjacent said instrumentalities with approximate accuracy as to lateral directions, means for moving said instrumentalities convergently to turn the cover margins horizontally and to position the box in lateral directions, and means for then moving the box vertically while said instrumentalities are stationary and positioned to turn the cover margins down against inner faces of the box walls. 85

4. Mechanism of the class described comprising a plurality of convergently movable margin manipulating instrumentalities, means for moving a box with projecting cover margins to position below said instrumentalities, means for raising the box in relation to said instrumentalities to approximately position the box in the plane of convergent movement of said instrumentalities, and means for then moving the instrumentalities convergently whereupon they accurately position the box in lateral directions and also in relation to the stated plane of movement, the instrumentalities also acting in their convergent movement to turn the cover margins horizontally inward. 95

5. Mechanism of the class described comprising a plurality of convergently movable margin manipulating instrumentalities, means for moving a box with projecting cover margins to position below said instrumentalities, means for raising the box in relation to said instrumentalities to approximately position the box in the plane of convergent movement of said instrumentalities, and means for then moving the instrumentalities convergently whereupon they accurately position the box in lateral directions and also in relation to the stated plane of movement, the instrumentalities also acting in their convergent movement to turn the cover margins horizontally inward, and means for then moving the box and said instrumentalities relatively in a direction perpendicular to said plane of convergent movement whereby the instrumentalities 120 effect the infolding of the margins against inner faces of the box wall. 125

6. Mechanism of the class described comprising a plurality of convergently movable margin manipulating instrumentalities, 130

means for moving a box with projecting cover margins to position below said instrumentalities, means for raising the box in relation to said instrumentalities to approximately position the box in the plane of convergent movement of said instrumentalities, means for then moving the instrumentalities convergently whereupon they accurately position the box in lateral directions and also in relation to the stated plane of movement, the instrumentalities also acting in their convergent movement to turn the cover margins horizontally inward, means for then moving the box and said instrumentalities relatively in a direction perpendicular to said plane of convergent movement whereby the instrumentalities effect the infolding of the margins against inner faces of the box wall, and means for then operating said instrumentalities to press the margins in position.

7. Mechanism of the class described, comprising convergently movable devices for turning and pressing projecting upper box cover margins, means for feeding and positioning a box in relation to said devices, means associated with certain of said devices and acting when the devices move convergently to horizontally turn and secure projecting lower cover margins to the box bottom, and means acting during discharge movement of the box to additionally press and secure the bottom cover margins.

8. Mechanism of the class described, comprising convergently movable turning and pressing heads, each having means for operating upon an upper projecting box cover margin, means carried by certain of the heads for turning and pressing projecting lower cover margins on the box bottom, means for advancing and locating a box in margin-turning position, means for then simultaneously advancing said devices to turn the upper and lower cover margins horizontally, and means for again moving the box to effect turning of upper margins against inner wall faces.

9. Mechanism of the class described, comprising convergently movable turning and pressing heads, each having means for operating upon an upper projecting box cover margin, means carried by certain of the heads for turning and pressing projecting lower cover margins on the box bottom, means for advancing and locating a box in margin-turning position, means for then simultaneously advancing said devices to turn the upper and lower cover margins horizontally, means for again moving the box to effect turning of upper margins against inner wall faces, and means for then operating the devices to press the upper margins in position.

10. Mechanism of the class described, comprising convergently movable turning and

pressing heads, each having means for operating upon an upper projecting box cover margin, means carried by certain of the heads for turning and pressing projecting lower cover margins on the box bottom, means for advancing and locating a box in margin-turning position, means for then simultaneously advancing said devices to turn the upper and lower cover margins horizontally, means for ejecting the box and moving it onward, and means acting during the last named box movement to additionally press and secure the bottom cover margins in position.

11. Mechanism of the class described, comprising a plurality of convergently movable turning and pressing heads, each having relatively movable inner and outer bars, the inner bars having cam-shaped lower faces to adjust a box and turn upper cover margins horizontally, and the outer bars having inner faces projecting below the inner bars to finally adjust the box by wall engagement and to co-operate with the inner bars in pressing the upper cover margins.

12. Mechanism of the class described, comprising a plurality of convergently movable turning and pressing heads, each having relatively movable inner and outer bars, the inner bars having cam-shaped lower faces to adjust a box and turn upper cover margins horizontally, the outer bars having inner faces projecting below the inner bars to finally adjust the box by wall engagement and to co-operate with the inner bars in pressing the upper cover margins, means for moving a box to preliminary position in relation to said heads, means for then moving the box to position its upper shell edges substantially in the plane of the inner bar cam faces, and means for again moving the box after convergent movement of the heads to effect inturning of the cover margins by action of the inner bars, whereafter the co-operating inner and outer bars are moved convergently to press the margin.

13. Mechanism of the class described, comprising a plurality of convergently movable turning and pressing heads, each having relatively movable inner and outer bars, the inner bars having cam-shaped lower faces to adjust a box and turn upper cover margins horizontally, the outer bars having inner faces projecting below the inner bars to finally adjust the box by wall engagement and to co-operate with the inner bars in pressing the upper cover margins, means for moving a box to preliminary position in relation to said heads, means for then moving the box to position its upper shell edges substantially in the plane of the inner bar cam faces, means for again moving the box after convergent movement of the heads to effect inturning of the cover margins by action of the inner bars, whereafter the co-operating

inner and outer bars are moved convergently to press the margin, and an ejector acting after the pressing action to discharge the box.

14. In a machine of the class described, a plurality of convergently movable heads, and inner and outer turning and pressing bars carried by each head, the inner bars having beveled ends which engage when the heads are moved convergently to form a continuous inner peripheral abutment for pressing cover margins in co-operation with the outer bars.

15. In a machine of the class described, a plurality of convergently movable heads, and turning and pressing bars carried by the heads, the bars having beveled ends which engage when the heads are moved convergently, clearances being provided in the lower engaging faces of adjacent bars to prevent pinching of cover corner margins.

16. In a machine of the class described, a plurality of convergently movable turning and pressing heads, a bracket on each head, and a bar mounted in each bracket and free for longitudinal movement whereby the bars are automatically adjusted as their ends engage in the convergent movement of the heads.

17. In a machine of the class described, a turning and pressing unit including a base, a bracket thereon, a turning and pressing bar supported in the bracket for free end-wise movement, a co-operating pressing bar, and means for moving the last named bar toward and from the first one.

18. A machine of the class described, comprising a main frame, box feeding and positioning means therein, an adjustable frame member, box margin turning mechanism thereon, and gauge means located on the main frame and the adjustable frame member to indicate the proper positioning of the adjustable frame member for a particular box dimension.

19. A machine of the class described, comprising a main frame, box feeding and positioning means therein, an adjustable frame member, box margin turning mechanism thereon, and gauge means located on the main frame and the adjustable frame member to indicate the proper positioning of the adjustable frame member for a particular box height, the gauge arrangement being such that when the adjustable frame member is adjusted by proper spacing of the gauge member, the margin turning mechanism is properly positioned for action on the margins of boxes of the stated height.

20. A machine for turning and pressing projecting cover margins of strip-covered boxes, comprising a feed belt, a box elevator having stops against which successive boxes are positioned by the feed belt, an upper frame member supporting convergently movable turning and pressing heads, means for

moving the elevator to position a box in approximate relation to the heads, and means for moving the heads convergently to position the box and act upon its projecting cover margins.

21. A machine for turning and pressing projecting cover margins of strip-covered boxes, comprising a feed belt, a box elevator having stops against which successive boxes are positioned by the feed belt, an upper frame member supporting convergently movable turning and pressing heads, means for moving the elevator to position a box in approximate relation to the heads, and means for moving the heads convergently to position the box and act upon its projecting cover margins, each of said heads comprising an inner and an outer bar and means for moving them convergently.

22. A machine for turning and pressing projecting cover margins of strip-covered boxes, comprising a feed belt, a box elevator having stops against which successive boxes are positioned by the feed belt, an upper frame member supporting convergently movable turning and pressing heads, means for moving the elevator to position a box in approximate relation to the heads, means for moving the heads convergently to position the box and act upon its projecting cover margins, each of said heads comprising an inner and an outer bar and means for moving them convergently, and means for operating the elevator after convergent movement of the heads to effect inturning of box margins by co-operation with the inner bars and position the upper shell margins for pressing action by convergent movement of the bars of the respective heads.

23. A machine for turning and pressing projecting cover margins of strip-covered boxes, comprising a feed belt, a box elevator having stops against which successive boxes are positioned by the feed belt, an upper frame member supporting convergently movable turning and pressing heads, means for moving the elevator to position a box in approximate relation to the heads, means for moving the heads convergently to position the box and act upon its projecting cover margins, each of said heads comprising an inner and an outer bar and means for moving them convergently, and means for operating the elevator after convergent movement of the heads to effect inturning of box margins by co-operation with the inner bars and position the upper shell margins for pressing action by convergent movement of the bars of the respective heads, and an ejector acting after the pressing action to positively free the box and cause it to move downward with the descending elevator.

24. A machine for turning and pressing projecting cover margins of strip-covered boxes, comprising a feed belt, a box elevator

- having stops against which successive boxes are positioned by the feed belt, an upper frame member supporting convergently movable turning and pressing heads, means 5 for moving the elevator to position a box in approximate relation to the heads, means for moving the heads convergently to position the box and act upon its projecting cover margins, each of said heads comprising an inner and an outer bar and means for moving them convergently, means for operating the elevator after convergent movement of the heads to effect inturning of box margins by co-operation with the inner 10 bars and position the upper shell margins for pressing action by convergent movement of the bars of the respective heads, and a discharge conveyor to move the box away after it is freed from the stops by descent of the elevator.

25. A machine for turning and pressing projecting cover margins of strip-covered boxes, comprising a feed belt, a box elevator having stops against which successive boxes are positioned by the feed belt, an upper frame member supporting convergently movable turning and pressing heads, means for moving the elevator to position a box in approximate relation to the heads, means for moving the heads convergently to position the box and act upon its projecting cover margins, each of said heads comprising an inner and an outer bar and means for moving them convergently, means for operating the elevator after convergent movement of the heads to effect inturning of box margins by co-operation with the inner bars and position the upper shell margins for pressing action by convergent movement of the bars of the respective heads, a discharge conveyor to move the box away after it is freed from the stops by descent of the elevator, and means acting during the carry-off movement to additionally press certain of the cover margins.
26. Mechanism of the class described, comprising margin turning means, means for positioning a box shell with projecting cover margins in relation to said turning means, means for actuating the turning means to turn the cover margins horizontally, and means for then moving the box shell in the direction of its side walls while the turning means is relatively stationary and positioned to turn the cover margins vertically against adjacent shell wall faces.
27. Mechanism of the class described, comprising margin turning and pressing means, means for positioning a box shell with projecting cover margins in relation to said turning and pressing means, means for actuating the turning and pressing means to turn the cover margins horizontally, means for then moving the box vertically while said turning and pressing means are relatively stationary to turn the margins vertically inward against adjacent shell wall faces, and means for then operating the turning and pressing mechanism to press the cover margins.
28. Mechanism of the class described, comprising margin turning and pressing means, means for positioning a box shell with projecting cover margins in relation to said turning and pressing means, means for actuating the turning and pressing means to turn the cover margins horizontally and then by movement of the box while said turning and pressing means are stationary, to turn them vertically inward against adjacent shell faces, and an ejector to free the boxes from the turning and pressing means.
29. Mechanism of the class described, comprising a turning bar, means for positioning a box shell with a projecting cover margin in relation to the bar, means for moving the bar laterally to turn the cover margins horizontally, and means for then moving the box in relation to the bar at a right angle to the above stated bar movement to cause the bar to turn the margin vertically inward.
30. Mechanism of the class described, comprising a turning bar having a convex operating face, means for positioning a box shell with a projecting cover margin in relation to the bar, means for moving the bar laterally to turn the cover margins horizontally, and means for then moving the box in relation to the bar at a right angle to the above stated bar movement to cause the bar to turn the margin vertically inward.
31. Mechanism of the class described comprising turning and pressing devices including inner and outer bars, means for positioning a box shell with projecting cover margins in relation to the inner bar, means for moving said inner bar laterally to turn a cover margin horizontally, means for then moving the box vertically in relation to the bar to cause the bar to turn the margin vertically inward, and means for then operating the bars to press the margin in position.
32. Mechanism of the class described comprising at least two pairs of margin turning and pressing instrumentalities for operating upon foldable box margins, each of said instrumentalities including an inner and an outer bar, means for moving the bars convergently, and means for bodily moving the instrumentalities laterally, means for positioning a box with projecting foldable margins in relation to the inner bars of said instrumentalities when the latter are retracted, means for then advancing the instrumentalities laterally to turn the box margins horizontally by action of the inner bars, means for then moving the box vertically in relation to the inner bars whereby

the latter turn the margins vertically adjacent inner box surfaces, and means for then moving the bars convergently to press the margins.

- 5 33. Mechanism of the class described, comprising a plurality of turning and pressing devices movable in the same general plane in convergent and divergent directions, means for so moving the devices, each device including pressing means and a driver for said pressing means, and an actuator for energizing all of the drivers simultaneously.

10 34. Mechanism of the class described, comprising a plurality of turning and pressing devices movable in the same general plane in convergent and divergent directions, and means for so moving the devices, each device including pressing means and a hydraulic driver for said pressing means.

15 35. Mechanism of the class described, comprising a plurality of turning and pressing devices movable in the same general plane in convergent and divergent directions, means for so moving the devices, each device including pressing means and a hydraulic driver for said pressing means, and a hydraulic actuator for energizing all of the hydraulic drivers simultaneously.

20 36. Mechanism of the class described, comprising a plurality of turning and pressing devices movable in the same general plane in convergent and divergent directions, means for so moving the devices, and means for positioning a box part in relation to said devices and moving it in steps in relation to the general plane of said devices.

25 37. Mechanism of the class described, comprising a plurality of combined margin turning and pressing instrumentalities each including co-operating bars arranged for relative convergent and divergent movement and means for so moving the bars, means for moving said instrumentalities bodily convergently and divergently in relation to a certain point, means for positioning a covered box part with projecting cover margins in relation to said instrumentalities and for moving it in successive steps in relation to the general plane of said instrumentalities and with relation to the bodily movement of said instrumentalities and the convergent and divergent movement of their bars to turn in and affix the projecting cover margins to adjacent inner shell surfaces.

30 38. Mechanism of the class described, comprising a plurality of combined margin turning and pressing instrumentalities each including co-operating bars arranged for relative convergent and divergent movement and means for so moving the bars, means for moving said instrumentalities bodily convergently and divergently in relation to a central point, means for positioning a covered box part with projecting cover margins in relation to said instrumentalities and for moving it in successive steps in relation to the general plane of the box and said instrumentalities.

35 39. Mechanism of the class described, comprising a plurality of combined margin turning and pressing instrumentalities each including co-operating bars arranged for relative convergent and divergent movement and hydraulic means for so moving the bars, means for moving said instrumentalities bodily convergently and divergently in relation to a central point, and means for positioning a covered box part with projecting cover margins in relation to said instrumentalities and for moving it in successive steps in relation to the general plane of said instrumentalities and with relation to the bodily movement of said instrumentalities and the convergent and divergent movements of their bars to turn in and affix the projecting cover margins to adjacent inner shell surfaces, and a hydraulic actuator for all of said hydraulic means, operated in coordination with the stated movements of the box and said instrumentalities.

40 40. Mechanism of the class described, comprising a plurality of combined margin turning and pressing instrumentalities each including co-operating bars arranged for relative convergent and divergent movement and hydraulic means for so moving the bars, means for moving said instrumentalities bodily convergently and divergently in relation to a central point, means for positioning a covered box part with projecting cover margins in relation to said instrumentalities and for moving it in successive steps in relation to the general plane of said instrumentalities and with relation to the bodily movement of said instrumentalities and the convergent and divergent movements of their bars to turn in and affix the projecting cover margins to adjacent inner shell surfaces, and a hydraulic actuator for all of said hydraulic means, operated in coordination with the stated movements of the box and said instrumentalities.

45 41. In mechanism of the class described, a turning and pressing instrumentality comprising a base, means for moving it to and fro, co-operating presser bars on the base, and hydraulic means for operating said bars.

50 42. A machine of the class described comprising a frame, a slide thereon, a pressing and turning head adjustable on the slide, a turning and pressing bar carried by the head, a co-operating pressing bar movably carried by the head, and hydraulic means for relatively moving the bars.

55 43. A machine of the class described comprising a frame, a slide thereon, a pressing and turning head adjustable on the slide, a turning and pressing bar carried by the head, a co-operating pressing bar movably carried by the head, and hydraulic means for relatively moving the bars.

60 44. A machine of the class described comprising a frame, a slide thereon, a pressing and turning head adjustable on the slide, a turning and pressing bar carried by the head, a co-operating pressing bar movably carried by the head, and hydraulic means for relatively moving the bars.

65 45. A machine of the class described comprising a frame, a slide thereon, a pressing and turning head adjustable on the slide, a turning and pressing bar carried by the head, a co-operating pressing bar movably carried by the head, and hydraulic means for relatively moving the bars.

43. A machine of the class described, comprising a frame, box locating and elevating means therein, a top plate, means for adjusting it vertically, and margin turning and pressing means carried by the top plate.

44. A machine of the class described, comprising a frame, margin turning and pressing means thereon, box feeding means, box

guides co-operating therewith, and means for simultaneously adjusting the guides for 10 different lateral box dimensions.

Signed at New York city, in the county of New York and State of New York this 10th day of May A. D. 1926.

HARRY BRIDGMAN.
